LIQUID FUEL BURNER

Ernest L. Woolley, Providence, R. I.

Application February 19, 1936, Serial No. 64,733

14 Claims. (Cl. 158—1.5)

This invention relates to liquid-fuel burners adapted for use with steam boiler or other furnaces and consists in improvements in the means for regulating and controlling the volume of air supplied to the flame.

One object of the invention is to provide an improved air-register for supplying a maximum amount of air when the burner is operating at maximum capacity and a reduced amount of air in proportion to the reduction in oil feed and the size of the flame.

Another object of the invention is to provide for regulating the amount of air supplied through the register in such manner as to utilize the maximum available draft while maintaining a more uniform velocity of revolution of the air between the center and the edge of the flame.

Another object of the invention is to provide an adjustable air-register adapted to supply the minimum necessary quantity of oxygen for complete combustion of the fuel with any desired size of flame.

Another object of the invention is to provide an air-register having a plurality of concentric annular throats adapted to be used either separately or conjointly for supplying air to the flame as required.

Another object of the invention is to provide an air-register having a plurality of concentric throats with separate vanes or dampers for admitting the air therethrough and means for opening and closing the vanes progressively in sequence to regulate the air admitted through each or all of the throats.

Another object of the invention is to provide manually-operable means for actuating the vanes to control the air supply in proper ratio to the amount of feed of the fuel and the size of the flame.

Another object of the invention is to provide a self-contained compact register of the type indicated having its control-mechanism of simple structure and proof against derangement or getting out of order, while being adapted for manual operation without special skill or expertness on the part of the operator.

Further objects of the invention are set forth in the following specification which describes a preferred form of construction of the device, by way of example, as illustrated by the accompanying drawings. In the drawings:

Fig. 1 is a vertical sectional view through a conventional type of boiler front showing an oil-burner applied to the opening therein and embodying the present improved air-register for

regulating and controlling the amount of air supplied to the flame;

Fig. 2 is an end view of the apparatus shown in Fig. 1;

Fig. 3 is a composite perspective view showing the vanes for the circular dampers at the front of the register and illustrating the relative position of the means for operating the vanes;

Fig. 4 is a detailed sectional view on line 4—4 of Fig. 2 showing the arrangement of the damper-operating ring;

Fig. 5 is a detailed sectional view on line 5—5 of Fig. 2 showing the construction of the manually-operative means for regulating the dampers;

Fig. 6 is an end view of the register, part sectional on line 6—6 of Fig. 1, showing the vanes for the primary damper in closed position and illustrating their operating connections;

Fig. 7 is a similar view showing the primary vanes in open position.

Fig. 8 is a part-sectional view on line 8—8 of Fig. 1 showing the secondary vanes in closed position;

Fig. 9 is a similar view showing the damper-operating means and the secondary vanes moved to a position at the start of opening these vanes; and

Fig. 10 is a similar view showing the secondary vanes in full open position.

The present improved air-register is herein shown and described in connection with an oil-burner of the pressure-atomizing type as used with natural draft, but it is to be understood that the improvement is adapted for use with burners of other types, for example, those using forced draft. The invention in general consists in providing an air-register having two or more concentric annular throats each having an independent damper or shutter for controlling the ingress of air thereto, and means for operating the different dampers progressively in sequence to regulate the amount of air supplied to the flame in accordance with the size of the latter.

Referring to Fig. 1 of the drawings, 2 designates the masonry of the front wall of the boiler furnace which is covered by an outer shell or front plate 3. The present improved air-register is preferably embodied in a unitary structure adapted to be attached to the front of the boiler furnace and serving as the means for supporting the fuel feed-pipe and the burner at its end, and also the controls therefor. As herein shown the burner-support and air-register comprises an annular casing or sleeve 5 of slightly tapered form adapted to fit closely within the opening 55

6 in the front of the furnace and formed with a radial flange 7 at its outer end. The annular sleeve or member 5 is provided with perforated ears or lugs 8 on its periphery, see Fig. 2, which 5 receive bolts 9 projecting from the furnace-plate 3 with nuts screwed onto their ends to secure the sleeve fixedly in position. The sleeve 5 forms the outer boundary wall of the larger throat of the air-register and cooperating therewith is a concentric annular casing 10 which forms a second inner throat for the register. The inner annulus 10 is provided with a radial flange 11 at its outer end and the space between this latter flange and the flange 7 on the annulus 15 5 serves as the inlet opening for the air which is admitted through the outer throat.

The inner throat annulus 10 is supported from a radial flange or ring 14 suspended on bolts 15 screwed into the flange 7 of the outer throat 5. 20 Between the radial flanges 7 and 11 are mounted primary and secondary vanes 16 and 17 which are pivoted on the bolts 15, previously referred to, to adapt them to be operated to open and close the separate entrances to the register through the 25 throats 10 and 5, respectively. The means for operating the vanes 16 and 17 are preferably arranged as hereinafter described. The inner throat annulus 10 is supported from the radial flange 14 by means of studs 18. The studs 18 are 30 screwed into the flange 11 on the annulus 10 with their reduced ends passing through bosses in the radial flange or ring 14 and secured thereto by nuts 19, see Fig. 1.

A concavo-convex closure-plate 20 of frusto-conical form has its rim shouldered to fit snugly around the inner rim of the ring 14, being secured fixedly thereto by bolts 21 passing through lugs on the closure-plate and screwed into a thickened portion of the ring. The inner end of the closure-plate 20 is formed with an annular sleeve 22. Fitted within the bore of the sleeve 22 is a tube 25 which serves as an additional air-pipe surrounding the burner-pipe 30, to be later described. The closure-plate 20 is formed with a hub or boss 23 45 through which projects a rod 26 adapted to slide therein and serving to mount a coupling 27 for connecting the oil-supply pipe 28 with the burner-pipe 30. The parts of the coupling 27 are held together by means of a clamp 31 operated by a hand-screw 32, these elements being of substantially the same structure and arrangement as shown in my prior U. S. Letters Patent No. 1,843,411, dated February 2, 1932. The coupling 27 also comprises a valve 33 controlled by a hand-wheel 34 for regulating the feed of the fuel 50 through the burner-pipe 30. The tube 25 has an extended portion 24 secured to the coupling member 27 by means of a bolt 29, the arrangement being such that the burner-pipe 30, its surrounding air-pipe 25 and the coupling 27 may be adjusted axially of the air-register by sliding the rod 26 in its bearing in the hub 23. A pin 35 at the 55 end of the rod 26 is adapted to strike against the hub 23 to limit the forward sliding movement of the parts.

The fuel feed-pipe 30 is supported axially within the tube 25 by means of a spider member 36 70 formed with a sleeve surrounding the pipe and arms radiating therefrom to engage the inner wall of the tube. At the inner end of the feed-pipe 30 is a burner-tip 37 which may be of any usual type, for example, of the construction shown and described in my U. S. Letters Patent No. 1,843,411, previously referred to; this element of the burner

not being herein described in detail as it forms no part of the present invention.

Supported on the inner end of the air-tube 25 is a diffuser-plate 40 in the form of a frusto-conical flange having a hub 39 surrounding the tube and secured in place thereon by any suitable means as by welding. The diffuser-plate 40 is provided with a plurality of radial slits 41 through which the air passing through the inner throat 10 is diffused as it flows to the flame, indicated by the dash lines designated 42 in Fig. 1; it being understood that the oil fed through the pipe 30 and forced under pressure through the burner-tip 37 is atomized and sprayed outwardly therefrom to undergo combustion in a flame in the shape of a hollow cone having an included angle of approximately ninety degrees.

As before indicated, the primary and secondary vanes 16 and 17 for the dampers of the inner throat 10 and outer throat 5, respectively, are 20 pivoted on a plurality of studs or bolts 15 equally spaced around the flanges 7 and 14, the relative position of the vanes being shown diagrammatically in Fig. 3 of the drawings. The vanes 16 and 17 are of arcuate shape conforming to an annular 25 contour of a diameter equal substantially to the outer diameter of the flanges 7 and 14. The primary vanes 16 are narrower, substantially one-half the width of the secondary vanes 17, it being understood that the inlet to the secondary throat 30 5 is required to be much larger than that to the primary or inner throat 10. The vanes 16 and 17 have hubs extending clear across their width with the studs 15 passing through bores therein, and between the vanes is a relatively thin separator 35 ring or annulus 43 supported on the studs 15 and forming a continuation of the radial flange 11 on the inner throat 10. Through this form of construction an annular slot 44 is provided between the outer edge of the flange 11 and the inner edge 40 of the ring 43 for a purpose later explained.

The radial flange or ring 14 is provided with an offset portion 12 forming a circular seat or pocket 13 in which is rotatably mounted a damper-operating ring 46 connected to open and close the 45 vanes 16 and 17. The ring 46 is held in place in the annular pocket 13 by cleats 47, see Figs. 3 and 4, let into recesses in the side of the ring 14 and fastened in place by screws 48. The ring 46 has pins 50 projecting laterally or horizontally inward 50 therefrom with their ends passing through the annular opening or slot 44 between the edges of the flange 11 and ring 43. These pins 50 engage with cam-slots in depending webs or flanges 51 and 52 on the primary and secondary vanes 16 and 55 17, respectively, see Figs. 3 and 6 to 10, inclusive.

In the depending webs 51 of each primary vane 16 is a substantially V-shaped cam-slot 53 through which one of the pins 50 of the operating ring 46 passes. The cam-slot 53 has two 60 branches 54 and 55, the branch 54 being of arcuate shape of the same radius as the slot 44 and so positioned that it will aline therewith when the vanes are in open position as illustrated in Fig. 7 of the drawings. The other branch 55 of the cam-slot will then assume a position extending radially with respect to the axis of the register. The vanes 17 have similar cam-slots 58 70 in their webs 52, but these have an opposite relationship. Each cam-slot 58 has an arcuate branch 59 which is so positioned as to aline with the slot 44 when the secondary vanes 17 are in closed position, as shown in Figs. 8 and 9 of the drawings, and a straight branch 60 which extends radially when the vanes are in closed 75

position. The pins 50 on the operating ring 46 project through the slot 44 and into the cam-slots 58 of the secondary vanes 17, and due to the opposite relationship of the cam-slots of the two sets of vanes, when the ring 46 is first turned to open the primary vanes 16 the pins 50 will slide in the arcuate branches 59 without any operative effect on the secondary vanes 17. It will be understood that the operating ring 46 is turned in a clockwise direction to open the vanes so that initially the pins 50 slide in the radial branches 55 of the cam-slots 58 to swing the primary vanes 16 from a closed position, as shown in Fig. 6, to an open position, as shown in Fig. 7. At this juncture, if the operating ring 46 is further rotated in the same direction the pins 50 will slide in the arcuate portions 54 of the cam-slots 58 to maintain the primary vanes 16 open while at the same time engaging in the radial branches 60 of the cam-slots 58 of the secondary vanes 17 to open these latter vanes; the complete method of operation of the damper-vanes being more particularly described hereinafter.

Any suitable means may be provided for manually rotating the operating ring 46 to regulate the position of the vanes of the primary and secondary dampers. As shown most clearly in Figs. 2 and 5, the ring 46 is provided with rack-teeth 64 on its outer periphery which mesh with the teeth of a pinion 65. The pinion 65 is fast on the end of a shaft or spindle 66 which may be constructed integrally therewith as shown in Fig. 5. The shaft 66 is journaled in a bearing hub 67 on a plate 68 fastened to a projecting portion of the radial flange 14 by means of bolts 69, see Fig. 2. A crank-arm 70 is keyed to the outer projecting end of the shaft 66 and provided with a handle 71 for turning it and a pointer 72 projecting in the opposite direction. The bearing plate 68 has a circular boss 74 marked with graduations indicated at 75, see Fig. 2, with which the pointer 72 is adapted to register as the crank-handle 70 is turned to rotate the ring 46; whereby to indicate the position of the dampers to the operator at the front of the furnace. A hand-nut 73 screwed onto the threaded end of the shaft 66 may be employed to bind the crank-handle 70 against the boss 74 to maintain the adjustment. In the closure-plate 20 is a sight-opening 76, shown in Fig. 2, which is normally maintained closed by a cover 77 pivoted on a bolt 78.

The method of operation of the complete burner is as next explained. Liquid fuel is supplied from a suitable source and fed under pressure through pipe 28, coupling 27 and burner-pipe 30 to the burner-tip 37, whence it is discharged in a conical spray. The amount of feed is regulated by the hand-valve 33 and after the burner has been lighted the air supply is controlled by adjusting the primary and secondary dampers in the manner as next explained.

With a restricted feed of the fuel the air is supplied through the inner throat 10, being admitted at the circumference of the air-register at its outer end by opening the primary vanes 16. The vanes 16 are opened by turning the crank-handle 70 in a counterclockwise direction to rotate the operating ring 46 in a clockwise direction, as viewed in Fig. 2, through the inter-engagement of the rack-teeth 64 on the ring with the gear-teeth of the pinion 65. Assuming that both the primary vanes 16 and the secondary vanes 17 are closed, as indicated in Fig. 1,

the clockwise rotation of the operating ring 46 will first cause the pins 50 to slide in the straight branches 55 of the cam-slots 58 in the webs 51, see Fig. 6, to rock the primary vanes into open position, shown in Fig. 7, as the pins reach the end of said branches. During this movement of the operating ring 46 the pins 50 slide in the arcuate branches 59 of the cam-slots 58 in the webs 52 of the secondary vanes 17 without causing any movement of these latter vanes. The primary vanes 16 can thus be opened to any extent in accordance with requirements for admitting air through the inner throat 10 to feed it to the flame in proper volume when the latter is reduced in size.

When a greater capacity of the burner is desired the fuel feed is increased by regulating the valve 33 and the secondary vanes are opened to increase the draft and thereby the flow of air to the flame. The secondary vanes 17 are opened by continuing to rotate the operating ring 46 in the same direction as previously described to cause its pins 50 to ride into the radial branches 60 of the cam-slots 58 in the webs 52 on the vanes 17, see Fig. 9; thereby rocking the secondary vanes 17 to open position as illustrated in Fig. 10. The extent of opening of the secondary vanes may be varied in accordance with the size of the flame to control the flow of air through the outer throat 5. With the vanes open they act as baffles to collect the air circulating in the boiler-room to direct it down into the damper openings at the periphery of the register. A small amount of air is admitted at the front of the register to be drawn through the pipe 25 to 35 feed directly to the flame adjacent its axis, this being of advantage to avoid overheating the burner-tip. The air passing through the inner throat 10 reaches the flame through the slots 41 in the frusto-conical diffuser-plate 40, this element not being essential to the proper operation of the air-register but having advantages as later pointed out.

By adjusting the damper openings in the air-register through the means of the primary and secondary vanes air is supplied in proportion to the quantity of fuel burned under any particular condition as desired. When the feed is restricted, for a flame of relatively small diameter, the air is supplied through the inner throat only, 50 insuring proper mixture of the oxygen and fuel without excess air and as the feed is increased an additional supply of oxygen is provided through the outer throat 5.

In liquid-fuel burners of the present type, in 55 which the flame is produced by pressure atomizing, the flame takes the form of a hollow cone and for proper operating conditions the area of the throat of the air-register supplying oxygen to the flame should be substantially equal in 60 diameter to the outer diameter of the flame. In other words, the flame cone should extend across the whole extent of the throat through which air is supplied. Further, to preserve the shape of the flame the air should revolve within 65 the register and advance toward the burner-tip spirally, with little velocity longitudinally of the axis of the burner but with a high velocity of rotation. If this effect is not secured and the air permitted to rush toward the burner-tip 70 along the axis of the burner the flame will be depressed by the force of entering air and the requisite conditions for efficient mixture of oxygen with the fuel cannot be obtained.

In all types of air-registers previously used 75

the entering air revolves as a mass with a maximum velocity at the periphery of the throat and the velocities of other strata reduced in proportion to their distance from the axial center of the throat. Since the pressure at the outer periphery cannot be greater than the force which produces it, that is the draft within the furnace, it would follow that the draft at the outer periphery of the throat of the register is substantially the same as the draft in the furnace; but the draft at each stratum from the outer periphery toward the center or axis of the register is less than the draft in the furnace, reaching a minimum value at the center of the register.

15 Since the air velocities obtained vary as the radius from the axis, the mean velocity will be at a point midway between the axis and the periphery of the throat and it will therefore be seen that the maximum available draft pressure drop over the full extent of the register is not utilized so that the capacity of the register is thereby restricted. However, under normal conditions the pressures tend to equalize with the result that the air supply in the low negative pressure area rushes toward the high negative pressure in the furnace and the effect of this is to break down the shape of the flame and produce a pulsating motion in the air supply as this condition is alternately built up and then 20 dissipated through equalization.

30 The use of an air diffuser of considerable diameter immediately behind the burner-tip tends to ameliorate this condition by segregating the lowest negative pressure areas from the rest of the 35 register throat so that to a certain degree conditions are stabilized. However, the use of a large diffuser materially reduces the area available for air supply.

35 Due to the present improved construction of the register with the outer and inner throats having separate regulating dampers the air pressure and velocity differentials across the inner register throat are materially improved. As the air is supplied through three separate channels, the 40 outer throat 5, inner throat 10 and axial air-pipe 45 25, the full draft differential will be available in each channel. In the outer throat 5 the air velocity will be a maximum at the outer periphery of this throat and a minimum at its inner periphery so that the average air velocity will be at the 50 mean of the radii of the walls of this throat and the pressure differential across this annulus will be limited to the difference between maximum and minimum velocities transposed in terms of 55 pressure.

60 Likewise, in the inner throat 10 the same maximum velocity as realized in the outer throat will be available, this velocity being a maximum at the outer periphery of the inner throat and a minimum at the periphery of the diffuser-plate 40, with the air pressure differentials being limited to the annulus in question.

65 The additional air supplied through the axial pipe or tube 25 surrounding the feed-pipe 30 is under the full draft differential, but as the area of this annulus is small it is not required to regulate the supply therethrough. The air admitted at this point tends to stabilize the air condition on the inner or furnace side of the diffuser and, as before stated, is useful in preventing overheating of the burner-tip.

70 Since the areas of pressure differential across the register throat are materially reduced by dividing the throat into a plurality of separate annuli a smaller diameter of diffuser-plate can be 75

used, thereby increasing the effective area of the register throat as a whole and providing increased air capacity. Moreover, since the average air velocity across the full throat is much higher in the present improved form of construction than in previously used air-registers the air capacity of the register as a whole is materially increased. Further, since the areas of pressure differential have been reduced and the pressure differentials largely diminished, the air supply is free from pulsations, allowing a more accurate regulation of the supply and insuring maximum efficiency in combustion.

10 The present invention constitutes an important improvement in the art by providing conveniently-operated means for controlling the air supply to the flame in proportion to its size; reducing the pressure differentials in the air supply at the flame; and preventing fluctuations or pulsations in the air current as it meets the 20 flame.

15 By the use of the present improved air-register the ultimate efficiency in burning liquid fuel is secured by thoroughly oxygenating the fuel particles while supplying the minimum necessary 25 quantity of air for complete combustion. Thus, any excess of air which would dilute the products of combustion and diminish the temperature is avoided, while a most intimate contact is secured between the fuel particles and the oxygen. 30 From these advantageous results it is obvious that the invention provides for the utmost economy in fuel during all stages of operation of the burner.

25 While the present improved air-register is herein shown and described as embodied in a preferred form of construction it is to be understood that various modifications may be made, in the size, shape and arrangement of its parts without departing from the spirit or scope of the invention. Therefore, without limiting myself in 40 this respect, I claim:

35 1. An air-register for liquid-fuel burners comprising an annular casing, inner annular walls dividing the casing into a plurality of separate throats, a damper for each throat comprising a 45 plurality of vanes, and a common means for operating the vanes of the separate dampers to open or close the different throats in a predetermined sequence.

40 2. An air-register for liquid-fuel burners comprising a casing having its interior divided into a plurality of separate throats, dampers for the different throats, and means for operating the dampers in sequence to progressively open or close the throats to the ingress of air.

45 3. An air-register for liquid-fuel burners comprising a casing, inner walls in the casing dividing its interior into a plurality of separate throats having intake openings at the periphery of the casing, dampers in said openings, and means operative to open first one damper and then another in sequence.

50 4. An air-register for liquid-fuel burners comprising a casing having its interior divided into a plurality of throats with a separate intake opening for each throat, a damper for each throat, and a rotary member connected to open or close the dampers progressively in sequence.

55 5. The combination of a casing, partitions dividing said casing into a plurality of annular throats having separate intake openings, a damper in the intake opening of each throat and each damper comprising a plurality of vanes, and means connected to all the vanes and operable to 70 75

- open or close the vanes of first one damper and then another.
6. An air-register comprising a casing having its interior divided into a plurality of throats with separate intake openings, separate dampers in the openings and each damper comprising a plurality of vanes, a rotary operating ring, and cams operated from said ring to open the vanes of first one damper and then another.
7. An air-register comprising a casing having its interior divided into a plurality of annular throats with a separate intake opening for each throat, separate dampers for the intake openings and each damper comprising pivoted vanes formed with cam-surfaces, and a rotary operating ring having means engaging the cam-surfaces to open or close the vanes of the different dampers.
8. An air-register for liquid-fuel burners comprising a casing having its interior divided into a plurality of throats, said casing having separate intake openings at its periphery communicating with the different throats, a plurality of pivoted vanes in each intake opening having depending webs formed with cam-slots, an operating ring rotatably mounted on the casing, and pins projecting from the operating ring through the cam-slots in the webs of the vanes and operative to open or close the vanes when the ring is rotated in opposite directions.
9. A liquid-fuel burner structure comprising a central feed-pipe, a burner-tip at one end of the feed-pipe, a central air-tube surrounding the burner-tip, a casing surrounding the burner-tip and having its interior divided into a plurality of annular throats, said casing having separate intake openings at its periphery communicating with the different throats, a damper for each intake opening comprising a plurality of vanes, a rotary member, and means operative from said rotary member to open first the damper for an inner throat and then the damper for an outer throat.
10. An oil-burner structure comprising a central feed-pipe, a burner-tip at one end of said pipe, an air-tube surrounding the pipe and open at its opposite ends, a diffuser-plate at the end of the air-tube located adjacent the burner-tip and provided with a plurality of apertures, a casing surrounding the burner and air-tube, a partition within the casing dividing its interior into inner and outer throats, said casing having intake openings at its periphery leading into the different throats, a closure-plate at the outer end of the casing, dampers in the intake openings each comprising a plurality of vanes, a ring mounted for rotation on the closure-plate, and means operative from the ring to open the vanes of the damper for the inner throat and subsequently the vanes of the damper for the outer throat during the continued rotary motion of the ring.
11. An air-register comprising an annular casing, an annular wall disposed within the casing to divide it into a plurality of separate throats, a radial flange on said inner wall forming an intake passage to the outer throat, a closure-plate spaced outwardly from said radial flange and forming an intake passage to the inner throat, a plurality of pivoted vanes for closing the intake passages to the different throats, webs on said vanes formed with cam-slots each comprising an arcuate branch and a radial branch, a ring mounted for rotation about the closure-plate, and pins projecting laterally from said ring through the cam-slots in the webs of the vanes.
12. An air-register for liquid-fuel burners comprising a substantially cylindrical casing, a wall dividing the interior of the casing into a plurality of annular throats, said casing having a plurality of intake openings in its outer periphery arranged in axially-spaced relationship and communicating with the different throats, a separate damper for each intake opening, and a common means for operating the separate dampers to open or close the separate intake openings in a predetermined sequence.
13. An air-register for liquid-fuel burners comprising a substantially cylindrical casing, cylindrical walls dividing the interior of the casing into a plurality of separate throats, a radial partition extending between one of the cylindrical walls and the periphery of the casing to form separate air passages to the throats, said casing being provided with separate intake openings at the circumference thereof and at opposite sides of the partition, and a damper in each opening for regulating the ingress of air through the register.
14. An air-register for liquid-fuel burners comprising an annular casing, cylindrical walls within the casing, one of said walls having a radial flange at one end extending outwardly to the periphery of the casing intermediate the ends of the latter, a closure for closing the outer end of the casing, said inner walls and closure forming a plurality of separate throats, said casing having a plurality of intake openings at its outer periphery on opposite sides of the radial flange communicating with the different throats, dampers for said intake openings, and means for operating the dampers.

ERNEST L. WOOLLEY.
